UNITED STATES PATENT OFFICE.

ARTHUR F. CASE, OF CLEVELAND, OHIO, ASSIGNOR TO THE WELLMAN-SEAVIER-MORGAN COMPANY, OF CLEVELAND, OHIO, A CORPORATION OF OHIO.

GRAB-BUCKET.

1,331,455.

Specification of Letters Patent.

Patented Feb. 17, 1920.

Application filed May 15, 1919. Serial No. 297,260.

To all whom it may concern:

Be it known that I, ARTHUR F. CASE, a citizen of the United States, residing at Cleveland, in the county of Cuyahoga and 5 State of Ohio, have invented a certain new and useful Improvement in Grab-Buckets, of which the following is a full, clear, and exact description.

This invention relates to grab buckets especially of the clam shell type, and has for its principal object the provision of a bucket construction which is more efficient, more durable, and more satisfactory in operation than prior devices of this kind. 15 More specific objects are to house the jaw or shell operating mechanism in such a manner that the likelihood of abrasion by sand and the like is minimized; to reduce the number of operative parts and 20 weight, and at the same time to provide increased digging power; to provide a housing for the operating parts formed in two halves and consisting preferably of two similar steel castings which when bolted 25 together not only effectively incloses the parts to the exclusion of abrasive material, but forms a rigid support therefor, the design of the housing and of the operating parts inclosed thereby, being such as to 30 readily lend itself to production on a quantity basis.

Still further the invention aims to provide a construction wherein there is great rigidity resulting in maintenance of alignment of the jaws or shells, and one requiring little head room as compared with other buckets of equal capacity, and a comparatively small amount of rope to close and open the bucket which nevertheless is constructed to have a wide swing and reach of the jaws or shells. Still further the invention aims to provide a construction wherein there is a low center of gravity when the bucket is in open position, producing 45 stability when the bucket is resting on the material.

The invention may be briefly summarized as consisting in certain novel details of construction, and combinations and arrangements of parts which will be described in the specification and set forth in the appended claims.

In the accompanying sheets of drawings, wherein I have shown the preferred embodiment of my invention, Figure 1 is a

side view of the bucket with parts broken away, and with the shells or jaws shown by dotted lines in open position; Fig. 2 is an end view of the same; Fig. 3 is a top plan view of the same; Fig. 4 is a horizontal sectional view substantially along the line 4—4 of Fig. 1; Fig. 5 is a sectional view through the top of the housing substantially along the line 5—5 of Fig. 2; Figs. 6 and 7 are respectively a side view 65 and a top edge view of one side or half of the housing; and Fig. 8 shows the two halves of the housing with one half in end elevation and one half in section.

The shells or jaws 10, 10, of the bucket 70 may be of usual construction, these shells being supported through the medium of two sets of arms including a set of relatively short arms 11 which have their lower ends connected to cross shafts 12 mounted 75 in castings 13 at the upper outer corners of the shells and their upper ends fitted onto the squared ends of the transverse shaft 14 mounted and operated as herein-after described, and two sets of relatively 80 long arms 15, which at their lower ends are connected to the inner side portions of the jaws as shown at 16, and at their upper ends are connected by pins 17 mounted in ears 18 projecting from the upper central 85 part of a housing 19, forming one of the important parts of the invention.

In the major portion of the prior buckets, particularly those of considerable capacity, the operating parts, that is to say, the parts 90 which operate the shells, are supported in a built up structure which is more or less open, and which has the disadvantage of high cost of production and the objection that it does not exclude sand, dirt and the like, and also lacks sufficient rigidity to maintain the jaws in alignment.

In the present construction, however, all the operating parts except the arms 11, are supported and housed in the housing 19 100 consisting of two parts only, which are preferably steel castings, the two parts consisting of two similar or counterpart halves 19^a and 19^b bolted together by bolts 20 passing through flanges 21 at the meeting edges 105 of the two halves, the meeting faces of the two halves being in a plane parallel to the plane of movement of the shells or jaws.

The housing 19 contains three main compartments including a middle compartment 110

22 formed in an enlarged part of the housing, and two relatively narrow end compartments 23, 23, these compartments being separated from the middle compartment 5 by transverse walls or partitions 24 which are formed in both halves of the housing. In the upper part of the middle compartment or in a sub-compartment 22^a leading therefrom are supported two guide sheaves 10 25, 25, for the opening and closing ropes shown at 26, 26, in Fig. 1, these guide sheaves being supported on pins each mounted in one of the halves of the housing as shown in Fig. 2, and below the 15 guide sheaves 25 in the middle compartment 22, is a drum 27, with a relatively large flanged portion 27^a for the closing rope and a relatively small flanged portion 27^b for the opening rope.

20 It will be observed that the drum 27 is at right angles to the plane of movement of the jaws, and therefore at right angles to the meeting faces of the two halves of the housing. In other words, the axis of 25 the drum and drum shaft is parallel to the plane of movement of the jaws. This drum is secured to a shaft or center 28 adapted to turn in bearing bushing 29, in bearings 30 on the two parallel walls or partitions which 30 separate the middle compartment 22 from the end compartments 23, the bearings 30 being formed half in one half of the housing and half in the other half of the housing, and these bearing halves are bolted together 35 by bolts 31, which go through the narrow portions of the housing on opposite sides of the enlarged middle portion forming the middle compartment 22.

It might be mentioned at this point that 40 the right angle position of the drum with respect to the plane of movement of the shells or the positioning of the drum and drum shaft with the axis thereof parallel to such plane of movement is important inasmuch 45 as it is a factor in the attainment of features of compactness and solidarity, and permits the number of operating parts to be reduced to a minimum, while at the same time these operating parts and the support 50 therefor can be made in such mechanical form that maintenance of alignment of the jaws at all times is possible.

The drum 27 is secured to the middle of the shaft or center 28, and on the extreme 55 ends of this shaft and formed integral therewith are two bevel pinions 32 which engage bevel gear segments 33, secured to the two operating shafts 14, already referred to, these shafts being rotatably supported in 60 bearings 34, on the two halves of the housing, and being parallel to each other and directly opposite, but at right angles to the drum shaft 28. By forming the bevel pinions 32 integral with the drum shaft 28, these 65 pinions can be made small in size, thus per-

mitting maximum power multiplication for a given diameter of drum, and providing great digging power in the shells without requiring a drum and a housing of excessive size.

The ends of the shafts 14 project beyond the sides of the narrow portions of the housing, and they are squared as before stated, and have fitted thereon the ends of the operating arms 11. These arms 11 are maintained on the squared portions of the shafts by bolts 35 which pass partly through the ends of the arms 11 and partly through the squared portions of the shafts.

The middle compartment 22, that is to say 80 the drum compartment will have one or more hand-holds 22^b to permit the closing and opening ropes to be suitably reeved about the drum and sheave, which ropes will have their ends secured to the drum, and after passing one or more times in opposite directions around the closing and opening portions 27^a and 27^b respectively, these ropes pass part way around the guide sheaves 25 and then out through openings 36 at the 85 upper middle portion of the housing, these openings being formed in a two-part cover 36^a the parts of which meet or engage along the line of junction of the two parts of the housing, which cover can be removed to insert the ropes and for the removal of the sheaves 25 without taking apart the housing, the parts of the cover being bolted together and also to the upper part of the housing. This cover has rope guards 36^b cast integral 90 with it, which guards extend part way around the sheaves. However, the gear compartments 23 are wholly closed against the ingress of sand or other foreign particles which in prior buckets reduced the life of 95 the operating parts due to their abrasive action. The extreme ends of the gear compartment 23 have normally closed openings 37 for the application of lubricant, but these 100 openings are at all times, except when the lubricant is being applied, closed by plates 38 held by screws to the end portions of the two halves of the housing on opposite sides of the plane of the meeting faces of the 105 halves of the housing.

The inner sides of the two halves of the housing are provided in the portions forming the gear compartments 23 with horizontally and vertically extending ribs or flanges 39 and 40 (see Figs. 4, 6 and 7) and in the 110 portions forming the middle compartment they are provided on the transverse walls with arc-shaped ribs or flanges 41 and 42, which in addition to strengthening the housing, serve as rope guards, the rib 41 on one 115 side of the compartment 22 overlying the outer flange of the opening portion 27^b of the drum, and the rib 42 on the opposite wall of the compartment 22 overlying the outer flange of the closing portion 27^a as 120

will be seen by reference to Fig. 1. Likewise directly opposite the middle flange of the drum 27 there is an arc-shaped web 43 of substantial V-shape projecting inwardly 5 from each half of the housing (see Fig. 8). The two webs 43 on the two halves of the housing encircle the upper half of the drum, and these also serve as rope guards for the closing portion of the drum. At the top 10 these webs 43 merge into horizontal V-shaped webs 44 (see Figs. 2, 7 and 8).

The housing and operating parts are very easily assembled, it being only necessary to lay one-half of the housing down on the 15 assembling floor with the open side up, lay the drum 27 and shaft 28 in the halves of the bearings provided therefor in this half of the housing, to insert the operating shafts 14, and then fit the other half of the housing 20 into place, and bolt the two halves of the housing together.

To open the bucket, by pulling on the opening rope which extends around the smaller portion 27^b of the drum and at the 25 same time easing up on the closing rope, the drum and drum shaft are turned in a direction such as to turn the jaw operating shafts 14 so as to swing the jaws to the position shown by dotted lines in Fig. 1. This movement of the drum winds the opening rope on the relatively large flanged portion 27^a of the drum, it being understood that the movement of the drum and drum shaft is transmitted by the bevel gearing 32 and 33, 30 so as to rotate the shafts 14 in opposite directions and that the movement is transmitted from these shafts 14 to the jaws of the bucket by the arms 11, the swinging movement thus imparted to these arms 40 causing the jaws to be swung to the positions stated.

To close the bucket pull is exerted on the closing rope which turns the drum and drum shaft in the reverse direction causing 45 the jaws to be swung from the dotted line position to the full line position in Fig. 1.

It will be sufficient to state without repeating in detail the several advantages of the bucket, that with the construction above 50 described, the objects and advantages enumerated at the beginning of the specification are obtained to a very high degree.

While I have shown only the preferred construction, it will be apparent that 55 changes may be made in details of construction and arrangement without affecting the principal features of the bucket, and I aim in my claims to cover all modifications which do not involve a departure from the 60 spirit and scope of my invention in its broadest aspects.

Having described my invention, I claim:

1. In a grab bucket, a pair of bucket jaws, a multi-compartment housing supporting the 65 jaws, an operating drum and drum shaft

mounted in the middle portion of the housing, shafts mounted in the housing and connected with the drum shaft so as to be turned thereby, and arms connecting the shafts to the jaws, the connecting means 70 between the drum shaft and last mentioned shafts being in closed compartments of the housing.

2. In a grab bucket, a pair of jaws, an operating shaft having its axis substantially 75 parallel to the plane of movement of the jaws, a pair of shafts at right angles to the first mentioned shaft and connected thereto so as to be operated by the same, means connecting said last mentioned shafts to the 80 jaws, and means for supporting said shafts.

3. In a grab bucket, a housing having three compartments including a middle compartment and two end compartments, a drum in the middle compartment, a shaft 85 carrying the drum, shafts extending through the end compartments and connected to the first-named shaft, a pair of bucket jaws, and operating arms connecting the last mentioned shafts to the jaws. 90

4. In a grab bucket, a housing having three compartments including a middle compartment and two end compartments, an operating drum mounted in the middle compartment and having a shaft projecting into 95 the end compartments, two shafts mounted in the end compartments at right angles to the first mentioned shaft, gearing connecting the first mentioned shaft to the last mentioned shafts, arms connected to said 100 shafts, and a pair of bucket jaws supported from the housing and connected to said arms.

5. In a grab bucket, a housing having three compartments including a middle compartment and two end compartments, 105 an operating drum mounted in the middle compartment and having a shaft projecting into the end compartments, two shafts extending through the walls of the end compartments at right angles to the first mentioned shaft, gearing connecting the first mentioned shaft to the last mentioned shafts, arms connected to said shafts, and a pair of bucket jaws supported from the housing and connected to said arms, said 110 end compartments being closed and separated from the middle compartment.

6. In a grab bucket, a housing composed of two cast plates bolted together, and having transverse partitions dividing the interior into three compartments, a drum in the middle compartment, a drum shaft supported in said partitions and projecting into the end compartments, a pair of shafts journaled in the walls of the end compartments, a pair of bucket jaws, and arms connected to said last mentioned shafts and to the jaws. 120

7. In a grab bucket, a pair of bucket jaws, a housing, jaw operating members in- 130

cluding a drum supported by the housing with its axis parallel to the plane of movement of the jaws, a pair of shafts supported by the housing at right angles to the axis 5 of the drum, said shafts being connected to the drum so as to be turned thereby and being connected to the jaws so as to operate the same.

8. In a grab bucket, a pair of jaws adapted 10 to swing toward and from each other, a housing having transverse walls, bucket operating parts supported by said housing and comprising a drum with its axis parallel to the plane of movement of the jaws and 15 having a shaft mounted in said transverse walls, a pair of shafts at right angles to the first mentioned shaft and geared thereto, and operating arms connecting the jaws to the last mentioned shafts.

20. 9. In a grab bucket, a pair of jaws adapted to swing toward and from each other, a housing composed of two members bolted together and having transverse walls forming compartments including a middle compartment and two end compartments, a drum having its axis substantially parallel 25 to the plane of movement of the jaws, a shaft supporting the drum and mounted in said transverse walls, a pair of jaw operating 30 shafts supported in the walls of the end compartments, gearing connecting the first mentioned shaft to the last mentioned shafts, supporting arms connecting the jaws to the housing, and operating arms connecting the jaws to said last mentioned 35 shafts.

10. In a grab bucket, a pair of jaws, a housing having an enlarged middle portion and relatively narrow end portions, a drum 40 supported in the middle portion with its axis parallel to the plane of movement of the jaws and having a supporting shaft whose ends project into the end portions of the housing, jaw operating shafts extending 45 through the walls of the end portions of the

housing, gearing connecting the first mentioned shaft to the last mentioned shafts, supporting arms connecting the jaws to the housing, and operating arms connecting the jaws to the ends of said last mentioned 50 shafts.

11. In a grab bucket, a pair of jaws, a housing having an enlarged middle portion and relatively narrow end portions, the end portions of the housing having two closed 55 compartments, a drum supported in the middle compartment with its axis parallel to the plane of movement of the jaws and having a supporting shaft whose ends project into the closed compartments, jaw operating 60 shafts extending through the walls of the relatively narrow portions of the housing, gearing connecting the first mentioned shaft to the last mentioned shafts, said gearing being in the closed compartments, supporting 65 arms connecting the jaws to the housing, and operating arms connecting the jaws to the ends of said last mentioned shafts, said housing being formed of two recessed cast metal plates united at the center plane of 70 the housing.

12. In a grab bucket, a pair of bucket jaws adapted to swing toward and from each other, a housing inclosing bucket operating parts including a drum at the middle 75 portion of the housing, with its axis parallel to the plane of movement of the jaws, a drum shaft supporting the same, a pair of jaw operating shafts rotatably supported by the housing on opposite sides of the drum, operating arms connecting the jaws to said last mentioned shafts, a power multiplying 80 gearing between the first mentioned shafts and the last mentioned shafts and including pinions formed integral with the first mentioned shaft.

In testimony whereof, I hereunto affix my signature.

ARTHUR F. CASE.
